B. Morgenthau INVENTOR
BY *Sigmund Herzog* ATTORNEY

UNITED STATES PATENT OFFICE.

BERNARD MORGENTHAU, OF NEW YORK, N. Y.

LOCK

1,410,829.

Specification of Letters Patent. Patented Mar. 28, 1922.

Application filed November 22, 1919. Serial No. 340,000.

To all whom it may concern:

Be it known that I, BERNARD MORGENTHAU, a citizen of the United States, and a resident of New York, in the county of New York and State of New York, have invented certain new and useful Improvements in Locks, of which the following is a specification.

The present invention relates to locks, and has for its main object to provide one with a sliding and rotary locking bolt, that is actuated by a rotary element, said element being adapted to be operated from the outside by means of a key and from the inside by a knob, the arrangement being such that the said rotary element may be disconnected from the key-actuated mechanism, so that the door cannot be opened from the outside.

Another object of the invention is to provide a lock of the character mentioned which is simple in construction, efficient in operation, and which it is practically impossible to pick either by skeleton or false keys or by sharp-pointed instruments.

A still further object of the invention is to provide a lock of the character mentioned which is adapted for manufacture on a commercial scale, or in other words one which is not so difficult to make as to be beyond the reasonable cost of such a device.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawings, in which:—

Figure 1 is a front elevation of a lock constructed in accordance with the present invention; Fig. 2 is a section taken on line 2—2 of Fig. 1; Fig. 3 represents a front elevation of the lock, partly in section, with the face plate removed to show its interior mechanism; and Fig. 4 is a section taken through a detail of construction.

In the drawings, the numeral 10 indicates

a lock casing, mounted in any suitable manner upon the inner face of the door 11, said lock casing being in alignment with a keeper 12 on the jamb 13. The lock casing is provided in its end plate 14 with a screw-threaded opening 15, said opening being in registering position with a screw-threaded cylindrical recess 16 in the keeper. With these two sets of threads are adapted to mesh the threads 17 of a cylindrical locking bolt 18, the latter being slideable in the direction of its longitudinal axis upon an arbor 19, that extends into the hollow hub 20 of a bevel gear 21. The arbor is attached to the said hub by any suitable means, for instance by a pin 22, passing through these two elements. The hub of the bevel gear is rotatably mounted in a bearing 23, the latter being either made integral with or attached to the back plate 24 of the lock casing. In order to transmit the rotation of the bevel gear 21 to the sliding bolt 18, any suitable means may be provided, for instance the arbor 19 may be made of polygonal cross-section, in the case illustrated in the drawings of square cross-section, and fit into a longitudinal bore 25 of square cross-section in the bolt 18. This bore is of a length to permit of a sliding motion of the said bolt on the said arbor.

The bevel gear 21 meshes with a similar gear 26, that is rotatably mounted upon a sleeve 27, the latter being rotatably mounted in the back plate 24 and held against longitudinal movement thereon. The cylindrical hub 28 of the bevel gear 26 extends beyond the sleeve 27, it being provided in its free end with a slot 29, that is adapted to register with a slot 30 in the free end of the sleeve 27. These two slots extend to the same plane in the sleeve 27 and bevel gear 26, as clearly appears from Fig. 4 of the drawings, for a purpose hereinafter to be described. Into the sleeve 27 extends a spindle 31, carrying a pin 32, that is adapted to enter the two slots mentioned. This spindle is rotatably mounted in the face plate 33 of the block casing and carries outside of the said casing a knob 34. The spindle is shiftable in the direction of its longitudinal axis upon said face plate, and has interposed between the said face plate and an enlargement 35 on the spindle a spring 36, which has a tendency to seat the pin 32 in the slot 30. The depth of the slot 29 in the bevel gear 26 is such that a shifting of the spindle 31 will not disengage the pin from the last-mentioned slot.

Upon the outer face of the face plate 33 is shiftably disposed a catch 37, which may be interposed between the knob 34 and the face plate 33, to hold the spindle 31 in its outer position, in which its pin 32 is disengaged from the slot in the sleeve 27.

The inner end of the sleeve 27 is closed by a head 38, having a slot 40, in which is seated a projection 39 upon a key plug 41, mounted 10 and adapted to turn in a cylinder 42. This plug and cylinder form part of a so-called "cylinder" lock, a detailed description of which is not necessary as it is well-known and does not form part of the present invention. The key is insertable into the key plug from the outside, the plug being fixed, that is to say non-rotatable, in case the key is withdrawn therefrom, as usual in constructions 15 of this type.

20 The operation of this device is as follows:— In the positions shown in Figs. 2 and 3 of the drawings, the locking bolt 18 is shown in its projected position, and the catch 37 disengaged from the knob 34. In these positions, the pin 32 is seated in the registering slots in the sleeve 27 and bevel gear 26. The door is unlocked from the outside by inserting a key into the plug 41 and turning the latter in the required direction, the rotation 30 of the plug being transmitted by the projection 39 to the sleeve 27 and by the intermediary of the pin 32 to the bevel gear 26. This gear, in turn, rotates the gear 21 and the arbor 19 fixed thereto, with the result 35 that the locking bolt 18 is turned and shifted longitudinally upon the said arbor toward the bearing 23. The rotating and shifting movement of the bolt unmashes the threads of the latter from the threads in the keeper 40 12, the door being adapted to be opened as soon as such unmashing has taken place.

In order to unlock the door from the inside with the elements in the positions shown in Figs. 2 and 3 of the drawings, the spindle 45 31 must first be shifted outwards and the catch 37 interposed between the knob 34 and the face plate 33, to hold the pin 32 disengaged from the sleeve 27. If now the knob 34 is rotated in the proper direction, the locking bolt will be disengaged from the keeper 12. It is to be observed that, when 50 the catch 37 is interposed between the knob 34 and the face plate of the lock, the door cannot be unlocked from the outside, inasmuch as there is no driving connection between the sleeve 27 and the bevel gear 26.

What I claim is:—

1. In a lock, the combination with a casing, of a longitudinally shiftable and rotatable locking-bolt therein, the outer end of said bolt being screw-threaded and adapted to be projected through said casing for engagement with a screw-threaded keeper, a rotatable arbor on which said locking-bolt 60 is longitudinally shiftable connected with

said bolt to transmit its rotation to the latter, a gearing operatively connected with said arbor, manually operated means for actuating said gearing, key-operated means for actuating said gearing, and means for disconnecting said key operated means from said gearing without disrupting the connection between the latter and said manually operated means.

2. In a lock, the combination with a casing, of a longitudinally shiftable and rotatable locking-bolt therein, the outer end of said bolt being screw-threaded and adapted to be projected through said casing for engagement with a screw-threaded keeper, a 70 rotatable arbor on which said locking-bolt is longitudinally shiftable connected with said bolt to transmit its rotation to the latter, a gearing operatively connected with said arbor, manually operated means for actuating said gearing, and key operated means for actuating said gearing, said manually operated means and said key operated means including a common element adapted to be disconnected from said key operated means without disrupting the connection between said manually operated means and said gearing.

3. In a lock, the combination with a casing, of a longitudinally shiftable and rotatable locking bolt therein, the outer end of said bolt being screw-threaded and adapted to be projected through said casing for engagement with a screw-threaded keeper, a rotatable arbor on which said locking bolt 95 is longitudinally shiftable connected with said bolt to transmit its rotation to the latter, a bevel gear fixed to said arbor, a bevel gear in mesh with said first-mentioned gear rotatably mounted in said casing, a key-operated sleeve loosely connected with said second-mentioned gear, manually operated means for actuating said second-mentioned gear, and selective means carried by said manually operated means for connecting or disconnecting at will said sleeve from said second-mentioned gear.

4. In a lock, the combination with a casing, of a longitudinally shiftable and rotatable locking-bolt therein, the outer end of said bolt being screw-threaded and adapted to be projected through said casing for engagement with a screw-threaded keeper, a gearing within said casing operatively connected with said bolt, manually operated means for actuating said gearing, key operated means for actuating said gearing, and means for disconnecting said key operated means from said gearing without disrupting the connection between the latter and said manually operated means.

5. In a lock, the combination with a casing, of a longitudinally shiftable and rotatable locking-bolt therein, the outer end of said bolt being screw-threaded and adapted 130

to be projected through said casing for engagement with a screw-threaded keeper, a gearing within said casing operatively connected with said bolt, manually operated 5 means for actuating said gearing, and key operated means for actuating said gearing, said manually operated means and said key operated means including a common element adapted to be disconnected from said key 10 operated means without disrupting the connection between said manually operated means and said gearing.

6. In a lock, the combination with a casing, of a locking-bolt therein adapted to be

projected through said casing for engagement with a keeper, manually operated means for actuating said locking-bolt, key operated means for actuating said locking-bolt, and means for disconnecting said key-operated actuating means from said bolt 20 without disrupting the connection between the latter and said manually operated actuating means.

Signed at New York, in the county of New York and State of New York, this 28th 25 day of October, 1919.

BERNARD MORGENTHAU.
